UNITED STATES PATENT OFFICE.

JULIUS GARST, OF WORCESTER, MASSACHUSETTS.

LOOM FOR WEAVING SHORT-WEFT FABRICS.

No. 902,286.

Specification of Letters Patent.

Patented Oct. 27, 1908.

Application filed January 25, 1908. Serial No. 412,533.

To all whom it may concern:

Be it known that I, JULIUS GARST, a citizen of the United States, residing at Worcester, in the county of Worcester and State of Massachusetts, have invented a new and useful Loom for Weaving Short-Weft Fabrics, of which the following is a specification.

This invention relates to looms, and while capable of use for several varieties thereof, it is particularly adapted to be applied to that class of looms which are employed for weaving fabrics from separate short weft lengths to produce straw-matting, grass and reed carpets, and the like. In this class of looms the shed is ordinarily set to be wider at the place where the weft threads or strands are to be introduced than the fabric. In order to accomplish this, the reeds or reed-dents have heretofore been made movable along the lay so that they may be brought toward each other as the lay beats up.

The principal objects of the present invention are to provide improvements in the mounting and operation of the reed dents whereby said dents will be caused positively to move uniformly towards each other during the beating up of the lay. One feature of the invention, therefore, is the construction of mechanism whereby this result may be accomplished in a simple and efficient manner.

Another object of the invention is to provide an improved form of guard for the reed dents whereby the same is simplified and cheapened as far as cost is concerned, and whereby the reed-dents may be brought closer together than would otherwise be the case. This is accomplished by stamping the guards out of sheet metal and folding them over so as to embrace the respective reed-dents and placing the folded parts in staggered relation with each other so that they will not interfere with the closing up of the reed dents.

Further objects and advantages of the invention will appear hereinafter.

Reference is to be had to the accompanying drawings, in which,

Figure 1 is a sectional view taken transversely through the lay, of a short weft-weaving loom showing one way in which the invention may be applied thereto. Fig. 2 is a horizontal sectional view of the same parts above the frame showing the latter in plan. Fig. 3 is a perspective view showing one of the reed-dents, its guard, and the way in which the fabric is woven. Fig. 4 is a face view of

a blank for making one of the guards. Fig. 5 is a side elevation of the guard made therefrom. Figs. 6 and 7 are similar views of the other form of guard, and Fig. 8 is a view 60 showing how the weft strand is crimped up in the manufacture of the goods.

The invention is illustrated as applied to a loom having the usual harnesses 10, heddles 11, breast-beam 12, warp-board 13, and lay 14, the latter having as usual a horizontal bar 15. The lay as usual is provided with a series of reed-dents 16, but instead of being caused to move toward and from each other during the beating of the lay simply by the 70 pull of the warp threads, means is provided according to this invention for positively moving the reed-dents so as to cause them all to move uniformly independently of any variation in the tension of the different warp 75 threads. This means consists of guides for the reed-dents, these guides in the present instance being shown as mounted on a stationary frame 20 having a part 21 above the bar 15 and a part 22 below it. In each of 80 these parts is a series of guide-bars 23 separated from each other sufficiently to permit the reed-dents to slide between them, and constituting guides therefor. These guides are at a slight angle to each other, those in 85 the center being exactly transverse to the lay and gradually converging toward each other on both sides of the center, as indicated most clearly in Fig. 2. The reed dents are held on the lay at the top by fitting them 90 against a shoulder 24 thereon and applying a plate 25 to the front of their upper ends. This leaves a recess in the top of the lay for the upper ends of these dents and they fit therein in such a way that they can slide 95 therealong. The lower parts of the reed dents pass through the horizontal bar 15 and they are held up by a plate 26 entering a notch in each of the reed-dents. From this 100 it will be seen that the reed-dents are moved positively toward each other as the lay beats up, and consequently there will be no irregularity in the distances which separate them when they engage the previously woven part of the fabric. This insures absolute uniformity in the product and gives greatly improved results.

As has been the custom heretofore, the breast-beam is provided with a dog 30 which engages a lever 31 on the breast-beam on 110 each beat to operate a series of guards 32 to liberate the weft strand *a* from the notches 33

with which the reed dents are provided. The lever is operated through a guide bar 34 entering notches 35 in the guards as will readily be understood. Each of these guards is 5 preferably made of a piece of sheet metal having two side members 36 and a cross-bar 37 or 38. These can be stamped out in a very simple manner and then folded over as indicated in Figs. 5 and 7 to form a sheath in 10 the cross bar. The side pieces 36 are folded close together into contact and virtually constitute one element in the complete guard, but the cross-bars are folded over so as to leave a passage through them so that they 15 can be threaded on to the reed-dents. It will be noticed that the cross-pieces 37 and 38 are located at different heights on the guards. This is provided so that by placing 20 these two forms of guards alternately on the reed dents no two of the cross-pieces or sheathes will come together, and consequently the reed-dents can be brought more closely together than would be the case if the cross bars or sheathes were all of the same 25 height. This constitutes a very simple and inexpensive way of making these guards, and is an important feature of the invention.

Fig. 8 shows one of the weft strands as it is formed by this construction. It has angular 30 indentations 40 alternately arranged on opposite sides for receiving the warp threads. These are formed when the weft strand is in a moist condition, and by the contraction of the same on account of the movement of the 35 reed-dents when all of them are in contact with the weft sufficient stock is gathered together to permit this shape to be formed.

While I have illustrated and described a preferred form of the invention, I am aware 40 that many modifications may be made therein by persons skilled in the art without departing from the scope thereof as expressed in the claims. Therefore I do not wish to be limited to the particular form shown and 45 described, but

What I do claim is:—

1. In a loom the combination with the lay of a frame in fixed position and having converging guides, and reed dents movably 50 mounted on said lay and guided in said frame.

2. In a loom for making short weft fabric, the combination with the lay, of a frame in fixed position and having guides converging 55 toward the warp board, and reed dents movably mounted in said guides, whereby the reed dents are uniformly brought nearer together across the fabric as the lay beats up.

3. A loom having a lay, reed dents 60 mounted on the lay, and movable longitudinally thereon, and means for positively and uniformly moving said reed dents on the lay, toward each other during the beat of the lay to assist in crimping the weft.

65 4. A loom having a lay, transverse guides,

each guide located at a slight angle to the next one, and reed dents mounted to be moved along said guides.

5. In a loom the combination with the lay, of a fixed frame having upper and lower reed 70 dent guides consisting of bars fixed to said frame and transversely placed with respect to the lay, and movable reed dents mounted in said guides.

6. In a loom the combination of a fixed 75 frame having reed dent guides located transversely to the lay but at a slight angle to each other, reed dents in said guides, and a lay connected with said reed dents and having means for moving them along as the lay 80 beats up, said reed dents being movable longitudinally to the lay.

7. In a loom the combination with the lay having a passage therethrough and reed 85 dents extending through said passage, of a stationary frame having reed-dent guides above and below said passage for said reed dents.

8. In a loom the combination with the lay having a horizontal bar provided with a passage therethrough, and reed dents extending through said passage, of a stationary frame having reed-dent guides above and below said 90 passage for said reed dents, said guides converging toward the warp board, the reed 95 dent being movable along the lay by said guide as the lay beats.

9. In a loom the combination with a lay, having a plate removably fixed at the top thereof and spaced from the rear surface of the 100 lay, reed dents passing into said space and movable therein and extending through a horizontal part of the lay below, and reed dent guides engaging the top and bottom of said reed dents.

10. In a loom the combination with the lay, of movable reed dents thereon having notches therein and guards movable on the reed dents for covering said notches each 110 of said guards comprising a sheet metal plate doubled upon itself.

11. The combination of a reed dent having a notch and a guard movably mounted thereon and consisting of a single piece of sheet metal doubled upon itself and providing a sheath at the fold for receiving said 115 reed dent.

12. In a loom the combination with a series of reed dents, of a series of guards therefor each guard having a sheath for receiving its reed dent, said sheaths being alternately arranged at two elevations.

13. A guard for a reed dent consisting of a single piece of sheet metal having two vertical pieces at the sides and a cross bar for connecting said vertical pieces folded through at the center of the cross piece on a line parallel with said vertical pieces.

14. A guard for a reed dent consisting of a single piece of sheet metal having two side 130

pieces at the sides and a cross bar connecting said side pieces through the center of the cross piece on a central line parallel with said side pieces, said side pieces being brought 5 into contact but the cross bar being folded so as to leave a passage therethrough for the reed dent.

In testimony whereof I have hereunto set my hand, in the presence of two subscribing witnesses.

JULIUS GARST.
